Primary Examiner — Cynthia Ramirez*Assistant Examiner* — Xavier Marti-Santos(74) *Attorney, Agent, or Firm* — Morrison & Foerster LLP(57) **CLAIM**

We claim the ornamental design for a hand-dryer, as shown and described.

DESCRIPTION

FIG. 1 is a front perspective view of a hand-dryer showing our new design;

FIG. 2 is a front view thereof;

FIG. 3 is a rear view thereof;

FIG. 4 is a side view thereof;

FIG. 5 is a side view of the opposite side of FIG. 4;

FIG. 6 is a top view thereof; and,

FIG. 7 is a bottom view thereof.

The broken lines shown in the drawings illustrate portions of a hand-dryer that form no part of the claimed design.
